UNITED STATES PATENT OFFICE.

EVA BELKNAP, OF VANCOUVER, BRITISH COLUMBIA, CANADA.

ABDOMINAL SUPPORTER.

1,151,922.

Specification of Letters Patent. Patented Aug. 31, 1915.

Application filed January 7, 1914. Serial No. 810,753.

To all whom it may concern:

Be it known that I, EVA BELKNAP, a citizen of the United States, and a resident of the city of Vancouver, in the Province of British Columbia, Canada, have invented 5 certain new and useful Improvements in Abdominal Supporters, of which the following is a specification.

My invention relates to improvements in 10 abdominal supporters, and the object of my invention is to devise a supporter in which the line of actual support follows across the region below the abdomen in front and extends around the back by way of the hip 15 bones to the waist line, thus affording the support in the most natural manner and at the point where it is most required, while at the same time leaving the stomach and diaphragm absolutely free from undue pressure. 20

A further object is to devise an abdominal supporter which can be readily placed on the person and which, on account of the particular manner in which the back lacing 25 is permanently arranged, is capable of great evenness and flexibility of adjustment.

I attain these objects by the means illustrated in the accompanying drawings in which—

30 Figure 1 is a front view of my supporter. Fig. 2 is a rear view. Fig. 3 is a side view showing my supporter in place on the figure.

Similar figures of reference indicate similar parts throughout the several views.

35 1 represents the body section of my supporter, made of any suitable pliable material and adapted to extend around the front and sides of the body of the wearer and partially around the back, the back portion 40 being completed by means of an intermediate section 2, which is adapted to be detachably connected to the main body section by fasteners of any suitable type.

3 represents strengthening stays disposed 45 at suitable positions around the complete supporter.

4 is a V-shaped reinforcing strip secured to the front of the body section and at the lower point thereof, for the purpose of taking the supporting strain and to which the adjusting buckles are flexibly connected. 50 This V-shaped strip 4 is secured to the body section in such a manner as to leave its extremities free of the body section, these free ends 5 and 6 having a plurality of eyeleted openings, 7 and 8 respectively, therethrough.

9 are the adjusting buckles, which are connected to the strip 4 by means of the lacings 10, these lacings being passed through the eyeleted openings 7 and 8 and brought back to the buckles 9, to which their free ends are secured by any suitable means.

11 represents a row of vertically arranged eyeleted openings in the material in proximity to one end 12 of the complete supporter, while 13 represents a row of eyeleted openings in proximity to the other end 14 of the complete supporter and oppositely set to the openings 11.

The back lacing of my supporter consists 70 of two independent sets of lacing, as shown in Fig. 2, that is, the set of lacings 15, which is adapted to engage the end 12 of the supporter and the set of lacings 16, which engages the opposite end 14. The set of lacings 16 is shown incomplete, for the sake of clearness in the drawing; it, however, is a duplication of the set of lacings 15. Each of these sets of lacings 15 and 16 consists of a number of independent laces, each of 75 which laces serves a pair of eyeleted openings in each of the rows 11 and 13 respectively, being reeved therethrough to draw downwardly, when in position, in the manner clearly shown in Fig. 3. The free ends 80 of the laces are carried, respectively, to the belts 17 and 18, to which they are securely fastened by any approved means, such as the clasp 19.

85 20 are studs or buttons secured to the front of the supporter to which a sanitary belt or truss may be attached. Hose supporters may also be attached to the body section 1 in any suitable manner.

Having thus indicated the principal parts 85 of my invention I will now describe the manner in which it is used and its utility.

In operation, the fasteners connecting the intermediate section 2 to the body section 1 are disengaged, and the belts 17 and 18 are unbuckled, allowing the back lacing to be loosened, after which the supporter may be placed upon the person. The section 2 is then re-fastened to the body section 1, after which, the wearer, by grasping the belts 17 and 18 and drawing forwardly thereon, may draw the supporter in to the required tightness. When this is accomplished, the belts 17 and 18 may be reeved through their respective buckles 9 and engaged thereby to 100 keep the supporter in position on the person. The supporting members of the device 105

will then be in the positions shown in Fig. 3, and it will be seen, as indicated by the dotted line X—X, in Fig. 3, that the lower part of the abdomen is thus supported or carried from the waist in the strongest and most natural manner.

- Referring particularly to Fig. 3, the utility of my invention will be clearly seen, as it will be noted that, in abdominal supporters 10 in use at the present time, the tendency is to draw the abdomen inwardly by a pull on and across the front of the stomach, more with a view to the reduction of corpulence than the actual supporting of the abdomen. 15 In such abdominal supporters or belts, while the reduction of corpulence may be attained, little, if any, support is given to the lower parts of the abdomen, while the risk of injury to the delicate organs in that part of 20 the human frame through undue pressure is ever present. In my invention, I obviate such risk entirely, and support the lower part of the abdomen in a manner which is physically perfect.

What I claim as my invention is:
An abdominal supporter comprising a

body encircling belt having a depending front portion adapted to completely cover the lowermost portion of the abdomen, and adjustable straps extending forwardly and downwardly from the rear of said belt, a V-shaped strip having eyelets along the edges of the ends of the legs of the V said strip being secured centrally to the extremity of said depending front portion so that the lower edges of said depending portion and the strip coincide, said strip being entirely below the level of the rear bottom edge of the belt, lacings passing through said eyelets and buckles carried by said lacings, said buckles adjustably connecting with said forwardly and downwardly extending adjustable straps whereby a straight line of support is secured from back to front from the lowermost point of the abdomen to the small of the back.

Dated at Vancouver, B. C., this 22nd day of December, 1913.

EVA BELKNAP.
